UNITED STATES PATENT OFFICE.

GEORGE STUART, OF NEWCASTLE-UPON-TYNE, ENGLAND, ASSIGNOR TO SIR
W. G. ARMSTRONG, WHITWORTH & CO., LIMITED, OF SAME PLACE.

MECHANICAL PRIMER FOR GUNS.

SPECIFICATION forming part of Letters Patent No. 679,792, dated August 6, 1901.

Application filed February 4, 1901. Serial No. 45,898. (No model.)

To all whom it may concern:

Be it known that I, GEORGE STUART, engineer, a subject of the Queen of Great Britain, residing at Elswick Works, Newcastle-upon-Tyne, England, have invented certain new and useful Improvements in Mechanical Primers for Use with Guns, of which the following is a specification.

This invention has for its object improvements in mechanical primers. The primers are intended for use in axial vented guns, more especially heavy guns, where the shock in closing the breech is excessive. To insure that the striker of the primer shall not be thrown forward by severe jolting or rough usage when closing the breech-block of a gun, a hollow thin metal truncated cone is interposed between the striker and the detonator, and so long as it retains its form keeps the striker from being thrown forward. The strength of the cone can be regulated to suit the resistance required by increasing or decreasing the thickness of the metal. The rear and smaller end of the truncated cone may be closed and have a point extending inward from it to come in rear of the detonator and at a short distance from it, or the point might, if preferred, be carried by the striker itself and pass through a hole formed through the rear end of the truncated cone. The larger forward end of the cone may have an outwardly-extending flange around it to rest against one side of a ring by which the detonator is carried, and the ring and flange may be held in place between a shoulder in the hole bored through the head of the outer tubular case of the primer and a screw-plug screwing into the inner end of this hole. The plug has a hole through its center to allow the explosion to pass to the charge in the forward part of the primer-case.

The improvements are shown in the drawings annexed.

Figure 1 is a longitudinal section, and Fig. 2 is a rear end view, of the primer. Fig. 3 shows separately a longitudinal section of the forward end of the striker, and Fig. 4 a section of the metal cone used with it. Figs. 5 and 6 show similar views of modified forms of the striker and cone.

A is the outer tubular case, with solid rear

end, having a hole bored through it to receive the striker B. The head or forward end of the striker is enlarged in diameter and has in its front end a conical recess B'.

B' is a disk secured to the rear end of the striker. The disk lies in an enlargement of the rear end of the hole bored through the rear end of the outer case, and the enlargement is made deep enough to allow of the disk and striker being driven a short distance forward.

C is a disk detonator of ordinary construction lying in an enlargement of the forward end of the hole and held in place by a screw-plug D, screwed into this forward end.

D' is a hole bored centrally through the screw-plug D.

E is a flanged truncated cone of thin metal interposed between the striker and the detonator-disk.

E' is a flange extending outwardly around the larger end of the cone and entering between the disk and the shoulder, up to which the disk is held by the screw-plug. The rear end of the cone is closed and has a point E'' extending inwardly from this closed end.

The explosive charge of the primer is contained within the forward end of the case A, and this forward end is closed by a disk A'.

So long as the cone E retains its form it restrains the striker from being thrown forward; but when the striker is forcibly driven forward it bends the cone and drives its point E'' against the detonator and explodes it. The cone then forms a very efficient gas-check to prevent escape of gas from the rear end of the primer.

In the alternative arrangement shown at Figs. 5 and 6 the point is carried by the forward end of the striker and the cone is formed with a hole in its rear end, through which the point is to extend.

What I claim is—

1. The combination of the outer tubular case A having a hole extending centrally through its rear end, the detonator C held in the forward part of this hole, the striker B lying in the rear part of the hole and the hollow truncated cone E of thin metal interposed between the forward end of the striker and the detonator.

2. The combination of the outer tubular case A having a hole extending centrally through its rear end, the striker B lying in the rear part of the hole, the detonator-disk C lying across an enlargement of the inner end of the hole, the thin truncated metallic cone E interposed between the disk and the striker, its flange E' and the screw-plug D screwing into the inner end of the hole and serving to nip the disk C and flange E' between itself and the shoulder formed by the enlargement of the hole.

3. The combination of the outer tubular case A having a hole extending centrally through its rear end, the detonator C, the striker B and the thin truncated metallic cone E interposed between the detonator and striker having its rear end closed and a striker-point E² extending inwardly from this closed end.

4. The combination of the outer tubular case A having a hole extending centrally through its rear end, the detonator-disk C, the striker B, the thin truncated metallic cone E closed at its rear end, the striker-point E²

projecting inwardly from this closed end, the flange E' extending around the forward end of the cone and the screw-plug D serving to nip the disk C and the flange E' between itself and the shoulder formed by the enlargement of the hole. 30

5. The combination of the outer tubular case A having a hole extending centrally through its rear end, the striker B with enlarged head lying in this hole, the conical recess B' in the forward end of the head, the disk B² fixed on the rear end of the striker and lying in an enlargement of the rear end of the hole, the enlargement being made deep enough to allow of the disk and striker being driven a short distance forward, the detonator-disk C, the thin truncated metallic cone E, its flange E' and the screw-plug D serving to nip the disk C and flange E' between itself and the shoulder formed by the 40 enlargement of the hole. 45

GEORGE STUART.
